Patented May 28, 1912.

2 SHEETS—SHEET 2.

UNITED STATES PATENT OFFICE.

WILLIAM A. HANSEN, OF SAN FRANCISCO, CALIFORNIA.

GAS-ENGINE-STARTING DEVICE.

1,027,649.

Specification of Letters Patent.

Patented May 28, 1912.

Application filed December 13, 1910. Serial No. 597,025.

To all whom it may concern:

Be it known that I, WILLIAM A. HANSEN, citizen of the United States, residing in the city and county of San Francisco and State 5 of California, have invented new and useful Improvements in Gas-Engine-Starting Devices, of which the following is a specification.

My invention relates to a device for readily starting gas or internal combustion engines, and for automatically changing the proportion of air and gas under varying conditions of starting.

It consists in a combination of parts and 15 details of construction as will be more fully described and claimed by reference to the accompanying drawings, in which—

Figure 1 is a vertical section of the upper portion of an engine cylinder with valves 20 and other appurtenances. Fig. 2 is an exterior view of a portion of the engine showing the starting device. Fig. 3 is an enlarged section of the auxiliary vaporizer. Fig. 4 is a view of the charging, scavenging 25 and releasing valve. Fig. 5 is a partial sectional view of the thermostat. Fig. 6 is a plan view of the same.

It is the object of my invention to provide a means for starting an internal combustion 30 engine from a stationary condition; to provide a suitably rich mixture for starting the engine under varying temperature which may be present, and after starting, to automatically increase the proportionate air 35 supply.

A is a carbureter which may be of any suitable or well known description, with the usual float α and needle valve, to maintain the desired gasoline level, and 2 is a small 40 auxiliary vaporizer or carbureter which is employed in starting, and which may be conveniently attached to the main carbureter and receive gasoline therefrom through a supply pipe 3, which may be connected 45 with the float chamber of the carbureter A. By thus connecting these parts, the single float and float chamber serve to maintain the desired level of gasoline in both carbureters.

The flow of gasoline through this part of 50 the apparatus is effected when the engine is to be started by admitting air from a tank, or other source of supply under pressure, through a pipe 4, which discharges through a jet tube 5, as shown in Fig. 3; this tube 55 being in line with the discharge pipe or passage 6 which leads to the engine cylinders.

The force of the air jet passing through the nozzle 5 acts like an injector to draw the gasoline through the pipe 3, through the passages exposed by the needle valve 7, and thence through the transverse connecting passage 8 by reason of the suction caused by the air jet before described. This insures a rich mixture of gasoline and air, such as will be readily ignited by the ignition means supplied to the engine. This mixture is supplied directly to the engine cylinders through the pipe 6; and the manifold 9; thence by distributing pipes 10 to valves 11 through which the mixture may circulate so as to charge the cylinders. The valves 11 are well shown in enlarged Fig. 4, in which the plugs 12 are turnable by means of crank arms 13 connected with a rod, as 14, by which they may be moved simultaneously and the cocks all opened or closed. The plugs have two openings with corresponding inlet passage 18 and outlet passage 19, which allow for the circulation of the charge into and through the cylinders. 20 This device also serves as a pressure relief to allow the engine to be turned over easily when opened. When the engine is thus charged, the valves are closed and the charge being ignited the engine will be started, 25 after which the operation is continued in the usual manner by the charge drawn through the main carbureter A. When the engine is cold it is necessary that the starting mixture should be quite rich in order to start the engine with the least difficulty, but if the engine has been running and it is desired to 30 start it when heated, it will be necessary to reduce the richness of the mixture by admitting a greater proportion of air. This 35 is effected by means of a thermostat controlled valve 15, which controls an auxiliary supply of air of the starting device. 40

The thermostat 16 may be of any suitable or usual construction. As here shown, it 45 consists of two plates of metal, having different degrees of expansibility; these plates being secured together and fixed at one end, the other end carrying the valve 15 which 50 controls the auxiliary air opening 17. The pipe from this opening is shown at 9 α , and leads to the auxiliary vaporizer into which it opens, as shown at 9 α in Fig. 3. When the engine is to be started under these conditions, the auxiliary air which is supplied, is 55 controlled by the valve 15. When the engine is cold little or no air is drawn through

this valve 15, but when the engine is warm the necessary air for making combustible starting mixture with the gasoline will be supplied through the valve 15, which, as the 5 engine becomes heated, will be more fully opened, and thus supply the requisite proportion of air.

As soon as the engine becomes heated, the 10 heat passing through the exhaust manifold will be communicated to the thermostat 16, which is fixed to said manifold, and the operation of the thermostat will be to open the valve 15 to a greater degree, thus allowing a greater portion of auxiliary air to 15 enter and greatly reducing the richness of the mixture.

The pipe 6 has a small opening at its 20 lowest point 6^a so that any gasoline which might otherwise accumulate in this pipe may escape.

Having thus described my invention, what I claim and desire to secure by Letters-Patent, is—

1. In a starting device for gas engines, 25 the combination of an auxiliary vaporizer, means to supply air thereto under pressure to start the engine, and a thermostat acted upon by the varying heat of the engine, for automatically varying the air supply in 30 proportion to the supply of gasoline.

2. In a starting device for gas engines, an auxiliary vaporizer, means to supply air thereto under pressure to start the engine, and a means to automatically increase the 35 air supply, said means including a thermostat and an auxiliary air inlet controlled thereby.

3. A starting appliance for gas engines, 40 said appliance including an auxiliary vaporizer with a gasoline supply, an air pressure injector to deliver a mixture to the engine, an auxiliary air inlet connecting with the vaporizer, and a thermostat-actuated valve by which the auxiliary air is regu- 45 lated.

4. In a starting device for gas engines, an auxiliary vaporizer, a supply of air thereto under pressure, and a means to automatically regulate the mixture for a cold or hot 50 engine, said means including a thermostat-actuated valve which closes or opens the auxiliary air passage to the vaporizer, said valve being operated by the varying heat of the engine.

5. In a starting device for gas engines, an auxiliary vaporizer with an air nozzle, a transverse passage connecting with the gasoline and auxiliary air supply, and a discharge passage leading to the engine 55 cylinder, and a means connected with the

vaporizer for regulating the mixture for a cold or hot engine, said means including a thermostat and an auxiliary air inlet controlled thereby, said thermostat being acted upon by the varying heat of the engine. 65

6. In a starting device for gas engines, the combination of an auxiliary vaporizer or carbureter, a thermostat-actuated valve acted upon by the varying heat of the engine by which the mixture is regulated, 70 and means for conducting the explosive mixture from the vaporizer to the engine cylinders.

7. The combination with an internal combustion engine, and cocks having a plurality of passages, of a vaporizer using a thermostat acted upon by the varying heat of the engine to regulate the mixture for a cold or hot engine. 75

8. The combination with an internal combustion engine, an auxiliary vaporizer, cocks having a plurality of passages, and a thermostat acted upon by the varying heat of the engine to regulate the mixture for starting the engine. 80

9. The combination with an internal combustion engine, an auxiliary vaporizer, and cocks having a plurality of passages, of a thermostat acted upon by the varying heat of the engine to regulate and form a 90 combustible mixture to start the engine, said thermostat carrying a valve which opens or closes the auxiliary air opening to the vaporizer.

10. In a starting device for gas engines, 95 a vaporizer having a means for regulating and forming an explosive mixture, said means including a thermostat acted upon by the varying heat of the engine, said thermostat carrying a valve, and an auxiliary air 100 inlet controlled thereby, an air nozzle, a needle valve, a passage connecting with the gasoline and the auxiliary air opening, and a passage in line with the air nozzle.

11. A starting appliance for gas engines, 105 said appliance including an auxiliary vaporizer with a gasoline supply, an air injector to deliver a gaseous mixture to the engine, an auxiliary air inlet connecting 110 with the vaporizer, means for controlling the flow of air to the auxiliary inlet, and a valve controlling the gasoline supply.

In testimony whereof I have hereunto set my hand in the presence of two subscribing witnesses.

WILLIAM A. HANSEN.
